(57) **CLAIM**

The ornamental design for a measuring instrument for machine tools, as shown and described.

DESCRIPTION

1. Measuring instrument for machine tools

1.1 : Front

1.2 : Back

1.3 : Left

1.4 : Right

1.5 : Top

1.6 : Bottom

1.7 : Perspective

1.8 : Perspective

1. The articles concerning the subject design applications are measuring instrument for machine tools; the devices include optical line sensors with light-receiving elements being linearly arranged for primarily measuring tool diameters or tool alignment.
